CLAIM

The ornamental design for a container for tape and disc, as shown and described.

DESCRIPTION

FIG. 1 is a front elevational view of the container for tape and disc showing my new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof; and,

FIG. 7 is a perspective view thereof shown in use, the broken lines showing a portable tape player being for illustrative purposes only and forming no part of the claimed design.

FIG. 1

FIG. 2

*FIG. 3**FIG. 4**FIG. 5**FIG. 6**FIG. 7*
